COUPLING FOR CONDUITS OR THE LIKE

Arbel Eckert, R.D. 2, Hummelstown, Pa., and Percival
V. F. Kingswell, 401 Sutter Place, Lititz, Pa.

Filed Mar. 17, 1961, Ser. No. 64,364

Term of patent 14 years

(Cl. D91—3)

FIG. 1

FIG. 2

FIG.3

FIG.4

FIG.5

FIG. 6

FIG. 7

FIG. 1 is a front elevational view of a coupling for conduits or the like embodying our new design.

FIG. 2 is a top plan view thereof.

FIG. 3 is a side elevational view of one side thereof.

FIG. 4 is a side elevational view of the other side thereof.

FIG. 5 is a front elevational view thereof showing the clamp member and one-half the coupling pivoted to the open position.

FIG. 6 is a front elevational view of a modified form of the coupling shown in FIG. 1, the rear being substantially the same.

FIG. 7 is a top plan view of the modification shown in FIG. 6.

We claim:

The ornamental design for a coupling for conduits or the like, as shown and described.
